UNITED STATES PATENT OFFICE

MANUEL GARCÍA GÜEDE AND JACOBO CUTÍN, OF TUCUMAN, ARGENTINA

PARACHUTE

Application filed November 17, 1927, Serial No. 234,012, and in Argentina October 5, 1927.

The present invention has reference to parachutes and has for its object to provide an arrangement for carrying a parachute and facilitating its working, so as to insure the automatic and instantaneous opening of the parachute with absolute security.

The invention consists essentially in placing the parachute, folded in a suitable manner, inside a tube which is open at the end from which the parachute falls. This tube is fixed underneath the aeroplane, or in any other suitable place, by means of a support which allows it to oscillate. The top end of the folded parachute carries a ring which is retained by a spring in the top end of the tube, and can only be released by a strong pull thereon.

The other end of the parachute, to which are attached the cords, has another ring, to which is attached the cord fastened to the body of the aviator.

A light fastening is used to attach this ring to the lower end of the tube in such a manner as to prevent the parachute from falling out when not intended. When the aviator pulls on this string it breaks, and the parachute is released from the tube in a manner which facilitates its opening.

In order that the invention may be more easily understood, a drawing is attached to the present specification, illustrating one convenient form of the invention:

Fig. 1 is a side view of the tube containing the parachute.

Fig. 2 is a longitudinal section of the top end of the tube.

Fig. 3 is a longitudinal section of the tube showing the parachute folded in its interior.

Fig. 4 shows one convenient method of attaching the apparatus to an aeroplane.

Fig. 5 shows the parachute open.

Fig. 6 shows the tube in perspective seen from the lower end.

In accordance with the first three figures, the apparatus comprises a support 4, affixed to the underbody of the aeroplane. A horizontal axis 5 at the extremity of this support sustains the tube 3 in such a way that it may oscillate, although, normally, the tube is held

in a horizontal position by means of the spring 2. The point of oscillation is near the top end of the tube, and the swing of a quarter-circle which the tube is able to describe allows it, at the moment it is called into use, to assume a vertical position, thus facilitating the fall of the parachute from the lower end. The top end of the tube is closed by a conical cap 1, in the interior of which is the spring catch 6 in the form of clips, in the fingers of which is held the ring 7 attached to the apex of the parachute 11. This latter, conveniently folded in the manner shown in Fig. 3, occupies the top end of the tube, and beneath it are coiled the cords 8 which terminate in the ring 10, to which is also attached the cord fastened to the aviator. Through the ring 10 is passed a light fastening 9 attached to the edges of the tube opening, as may be better seen in Fig. 6.

In Fig. 4, the tube is shown at 3, and the cord fastened to the aviator at 13. The manner in which the cord runs from the aviator to the apparatus over the aeroplane may be clearly seen.

Fig. 5 shows an ordinary parachute open, 17 being the material, 16 the upper ring, 18 the sustaining cords, 14 the lower ring and 15 the cord by which the aviator is suspended.

The working of the apparatus is as follows: As soon as the aviator jumps from the machine and the cord attaching him to the parachute tautens, his weight causes the tube to swing down and the light fastening retaining the parachute in the tube is broken. The parachute leaves the tube and takes an elongated form due to the fact that its apex is retained by its top ring until the last moment. When the parachute is completely extended, the pull exerted upon it by the weight of the aviator frees the top ring from the spring clip, and releases the parachute from the aeroplane.

Owing to the elongated form which it has taken on leaving the tube, and being already unfolded, the parachute opens instantaneously, and immediately begins to exert its sustaining action.

The two principal advantages of the ap-

paratus are at once seen. The one is that absolute security in the working of the parachute is obtained. In fact, its action is automatic, that is to say that it does not depend upon the will of the aviator; and it is furthermore safe in its action in that it obviates any delay in the unfolding of the apparatus. The other advantage is the immediate opening of the parachute, thus obviating the unpleasantness of a fall through a relatively great space before the action of the parachute begins to be manifest, as happens when parachutes are carried upon the person of the aviator himself.

15 Claims:

1. A device for releasably supporting a parachute on an aeroplane including the combination with a parachute and its main supporting rope, an open ended casing for receiving the parachute in a folded position, a bracket attached to the undersurface of the fuselage for rockably supporting the casing, a closure cap detachably connected to the front end of the casing, coacting means on the cap and on the top of the parachute for detachably connecting the parachute to the cap, releasable means traversing the other end of the casing and engaged with the parachute and adapted to normally retain the parachute and its ropes within the casing and adapted to be released by a pull exerted when the aviator falls, a stop member on the casing, and a spring member mounted on the bracket and having its ends engaged with the stop member for normally holding the casing in a horizontal position but permitting the same to be moved to a vertical position as the parachute is being removed.

2. A device for releasably supporting a parachute on an aeroplane including in combination with a parachute and its supporting ropes, an open ended casing rockably supported on the under part of the aeroplane for receiving the parachute in a folded position, a closure cap detachably connected to the front end of the casing, coacting means on the cap and the top of the parachute for detachably connecting the parachute to the cap, a ring connected with the ropes of the parachute and receiving the main ropes, and a guard tied at its ends to opposite sides of the casing and traversing said ring at the outer end of the casing for normally retaining the parachute and its ropes within the casing and adapted to be broken by a pull exerted when the aviator falls.

3. A device for releasably supporting a parachute on an aeroplane including in combination with a parachute and its main supporting rope, an open ended casing rockably supported on the under part of the aeroplane for receiving the parachute in a folded position, a closure cap detachably connected to the front of the casing, a spring armed clasp on the inner part of the cap, a ring on the top

of the parachute normally arranged between the arms of the spring clasp whereby the parachute is detachably connected to the cap, and releasable means traversing the other end of the casing and engaged with the parachute and adapted to normally retain the parachute and its ropes within the casing and adapted to be released by a pull exerted when the aviator falls.

In testimony whereof they affix their signatures.

M. GARCÍA GÜEDE.
